FAÇADE FOR ELECTRIC HUMIDIFIER

Jack B. Schmitt, West Los Angeles, Calif., assignor to
Sunbeam Corporation, Chicago, Ill.

Filed July 5, 1972, Ser. No. 268,956

Term of patent 14 years

Int. Cl. D23—04; D06—04

U.S. Cl. D23—146

FIG. 1 is a perspective view of a façade for an electric humidifier embodying my new design;

FIG. 2 is an enlarged cross-sectional view taken along line 2—2 of FIG. 1; and

FIG. 3 is an enlarged partial cross-sectional view taken along line 3—3 of FIG. 1.

The humidifier is shown in broken lines in FIG. 1 for illustrative purposes only.

I claim:

The ornamental design for a façade for an electric humidifier, as shown and described.
